BOOK AND BOOKBINDING

William Ebenezer Elliott, Liverpool, England

Application June 22, 1931, Serial No. 546,081, and
in Great Britain August 26, 1930. Renewed
May 23, 1933

5 Claims. (Cl. 281—23)

This invention has reference to book bindings, and has for its primary object and effect to provide a construction or species of book binding by which the cost of binding units or bundles of 5 sheets of letter press or other sheets is rendered relatively inexpensive; but it also has reference to complete books in which the bindings according to the invention form part of same.

In cases where works or books or printed matter 10 are published, or issued as serials or as periodical publications, or in "parts" or sections, it is very often desired to have the series or set bound in stiff cases or bindings, so that they should constitute a proper bound book; but 15 usually the cost of such bindings is considerable and the owner foregoes doing so; and one of the chief objects and effects of the invention is to provide a method of manufacture and form of construction of binding that is relatively inexpensive, so that the owner is able to do what he 20 desires; and a further object and effect is to enable people who take in printed matter in series, or in the form of periodicals, to bind the books themselves, by merely having to purchase 25 the inexpensive cover—constructed in the manner herein set forth—which enables them to do the binding themselves.

A book binding according to this invention 30 comprises hard front and back covers and flexible back, and between the covers, there is attached by adhesive, adjacent to each edge or cover of the back proper, a multi-channelled or flanged device or devices or members, and the divisions or partitions or flanges of these devices 35 are spaced at suitable distances apart as may be required, and constitute attachment means or devices, to the sides of which, and by which the back parts of the members, parts, or sections 40 of printed matter to be bound can be attached or bound by an ordinary adhesive such as gum or paste. Consequently, according to the number of parts, serial members or periodical publications to be contained and bound within the 45 cover, there will be provided a corresponding number of attachment channels or flange devices provided in it.

The back edges of the parts or members or sections to be bound, are in the binding operation, placed in position between the partitions or flanges, and secured to their sides, or to their sides and the bottoms of the channels or spaces 50 by an adhesive, which may be provided or applied in any suitable way; and when this has 55 been done, and the adhesive has become dry, the

binding operations are complete, the result being the bound book.

According to one and an advantageous construction or form of the holding member or means, it is made of a sheet of paper or suitable material, and is formed with a plurality of continuous channels, the partitions between which are produced by suitably folding the paper or material so as to form tongues, and so channels; and in this case the paper is creased or scored 60 in any suitable known way, so that it can be folded along the creases to produce the multi-channels from top to bottom; and the adhesive, say a suitable gum, is provided on the surfaces of the tongues or partitions or partitions and 65 other parts. To the back of this attaching means there is adhered a reinforcing strip of textile or suitable strong material, so that these two parts become one when adhered together; and the textile fabric, carrying the paper or like 70 device is adhered to the inside of the case adjacent to the edges of the back, and thus the attaching or binding part or device is firmly held in position, but not attached to the back proper 75 of the case, and so the latter is free, as is necessary.

When the attaching or binding means or device 80 is of the folded kind as described, the folded parts forming the tongues or partitions which form the sides of the channels may be adhered 85 together, and to the outer of the channel partitions or members, the "end papers" of the book may be secured, so that they would lie next the outer sheets or pages of the bound parts or members.

In the binding action, the back portions of the parts of sections to be bound in the cover, may be wetted, say by dipping them into liquid; and then placed in the channels, and after all have been placed in position, the cover sections are 90 folded together, and the whole is put under a suitable weight, so that the channel tongues or partitions, and the parts or sections to be bound are firmly stuck together, and when dry, the binding operation is complete.

In some cases, the paper, or like attaching or holding means or device will be of the same width as the textile or like reinforcing portion; whilst in others it may extend and cover the whole of the interior surfaces of the cover boards, in which 100 case of course these two parts are in one, and the side portions or sheets constitute the linings of the cover.

In the case of bindings for inexpensive books, the cover may consist of boards enclosed in cov- 110

erings of any suitable material as now used in connection with inexpensive bindings.

The invention is illustrated in the annexed drawings, which give an example of binding according to this invention, Figures 1 and 2 being plan in section and inside face view respectively of the binding, and Figure 3, a plan in section of a bound book.

Referring to the drawings, 1 are the stiff sides 10 of the cover, and 2 is the back proper, which may be regarded as of ordinary inexpensive book cover construction. 3 is the material, say a suitable strong paper, of which the holding or binding portion or means is formed; and in the case 15 shown, this material is formed into a plurality of continuous longitudinal channels 4 of which 5 are the fastening or securing tongues or partitions, which form the channels; and 6 are the margins of the strip 3, which extend over the 20 inner portions of the inside of the cover sides.

7 is the textile or like material of a relatively 25 strong nature, to which the attaching or binding portion 3 is adhered by a suitable adhesive, and which is directly adhered by a suitable adhesive to the parts of the inside of the cover sides adjacent to the back proper 2. 8 are the usual "end papers".

In the case shown, the attaching or binding 30 channel tongues or partitions 5 are formed by folding a previously and suitably creased piece of paper or other suitable material 3, so that the adjacent folded parts lie one upon the other in the manner illustrated, and they are held together by an adhesive. When adhering the 35 two parts 1 and 7 together, the tongues of partitions 5 may be first pressed down flat, so that the channel part, and the textile or like part 7 may be conveniently pressed upon one another, and a firm adhesion produced.

40 While the binding described and illustrated in the drawings is advantageous, the invention is not restricted to this manner of formation; as for instance the projecting tongues or holding parts may be not continuous, as in the example 45 given, but may be provided by a plurality of tongue devices secured to the interior of the cover at spaced distances. The manner of applying and fitting and attaching the "parts" or 50 sections of printed matter, in the case, has been already described above.

What is claimed is:—

1. A book binding including a cover made up

655

660

665

670

675

of sides and a back, a multi-channeled holding member of flexible material folded longitudinally to provide spaced tongues of double thickness to provide binding channels, the holding member being extended in both directions beyond the channels to provide portions to be secured to the inner surface of the sides of the cover.

2. A book binding including a cover made up 80 of sides and a back, a multi-channeled holding member of flexible material folded to form spaced tongues to define channels, a relatively flat flexible member secured to the rear surface of the multi-channeled holding member, said flexible member and the multi-channeled holding member 85 beyond the channels being secured to the inner surfaces of the sides of the cover.

3. A multi-channeled holding member for use 90 in book binding comprising a flexible section folded upon itself at spaced intervals, with the inner surfaces of the folded portions adhesively connected, the folded portions providing spaced 95 tongues to define binding receiving channels, the holding member being extended in both directions beyond the channels to provide for securing the holding member in position as a part of the 100 binding.

4. A multi-channeled holding member for use 105 in book binding comprising a flexible section folded upon itself at spaced intervals, with the inner surfaces of the folded portions adhesively connected, the folded portions providing spaced 110 tongues to define binding receiving channels, the holding member being extended in both directions beyond the channels to provide for securing the holding member in position as a part of 115 the binding, and a flexible strip overlying and secured to the multi-channeled holding member throughout the side opposite the tongues.

5. A book including a cover in which a plurality of sections of matter are to be bound, comprising a multi-channeled device of flexible material 120 for retaining the sections, said device having a plurality of channels formed by tongues, the side portions of the device being secured to the inner portions of the sides of the cover, and a textile member secured to the inner portion 125 of the side of the cover and to which the margins of the multi-channeled device are adhered.
